UNITED STATES PATENT OFFICE.

EDWIN E. SLICK, OF WESTMONT BOROUGH, PENNSYLVANIA.

EXTENSION-RAILS.

1,177,657.

Specification of Letters Patent.

Patented Apr. 4, 1916.

Application filed January 29, 1916. Serial No. 75,004.

To all whom it may concern:

Be it known that I, EDWIN E. SLICK, a citizen of the United States, residing in the borough of Westmont, in the county of Cambria and State of Pennsylvania, (whose post-office address is Johnstown, Pennsylvania,) have invented certain new and useful Improvements in Extension-Rails; and I do hereby declare the following to be 10 a full, clear, and exact description of the invention, such as will enable others skilled in the art to which it appertains to make and use the same.

My invention relates to extension rails 15 which may be used in extending a railroad track to a working face by sliding over and in line with the track rails, in order to accommodate cars and other apparatus on these tracks and keep them close to their 20 work.

The illustration and description here- 25 with, I have shown a track composed of a pair of usual T-rails and over the ends of these I set my extension rails, which are of inverted U or channel section, which extension rails may be projected forward in line with the track rails so as to prolong the track as required and kept it close to the working face, until such time as the amount 30 of extension is equal to the length of one of the standard track rails which is used; whereupon the standard track rails are introduced in place of the extension rails and the extension set upon the new pair of 35 track rails. This process can be repeated indefinitely.

One of the advantages of my invention is due to the fact that it is impractical and uneconomical to cut track rails in short 40 pieces for the purpose of extensions, besides which a track so made cannot be kept in close contact with the working face and can only come as close as the fixed lengths of the track rails will permit; whereas by 45 means of my invention the track can be kept in close proximity to the changing location of the working face at all times.

My invention is particularly applicable in connection with coal-digging machines and 50 coal cars, which, in order to be operated successfully and economically, must be near the working face of the coal seam; and it is also equally applicable to steam shovels, quarry cars, channeling machines, ditch ex- 55 cavators, canal-diggers, sewer-ditch excavators,

tors, quarrying machines; or for use in ore mines, clay mines, salt mines, dump tracks for forming embankments, or for wasting earth, rock or other materials, and in fact any place where a car or other apparatus 60 has to progress gradually into a cut or entry.

For the purpose of simplicity of description and illustration, I have shown my extension rail in connection with a coal mine, but I wish it understood that it is equally 65 applicable to any other construction to which it is adapted.

Referring now to the annexed sheet of drawings forming part of this specification:—Figure 1 is a side elevation of the 70 end of a track in a coal mine entry or room, showing my extension rail in position and a mine car thereon close to the working face of the coal or other material; Fig. 2 is a top plan view of that portion of the track 75 illustrated in Fig. 1; Fig. 3 is a transverse sectional elevation on an enlarged scale taken on the line III—III of Fig. 1, and Fig. 4 is a transverse sectional elevation 80 through my extension rail, also on an enlarged scale, taken on the line IV—IV of Fig. 1.

Referring now to the various characters of reference on the drawings:—1 represents a mine entry or room in general, 2 is 85 the working face of coal, rock or other material which is in process of cutting or excavation, 3 is a mine car located on my extension rails close to the working face, so that the material can be readily loaded therein. 90 My extension rail is also adapted to the use of coal cutting machines, or other apparatus, which must, of necessity, be located close to the working face to undercut or shear this or to otherwise handle the material in any 95 way.

4 are the ordinary track rails, shown in this case as T-rails, the tracks being mounted on metallic ties 5, provided with buttons 6, these ties and their fastenings 100 being the subject of my prior patent for metallic tie, No. 1,125,888, dated January 19, 1915. My extension rails are indicated as 7, these being of inverted U or channel section, provided with a top portion 8, forming the tread thereof, side portions 9, and comparatively small laterally projecting base flanges 10, whereby the rails are adapted to be secured to the ties or gage rods by buttons, clips, spikes or other suitable means. 110

In order to permit the car or other apparatus mounted on wheels to easily pass from the track rail 4 to my extension rail 7, I prefer to bevel the top and upper portion of 5 the sides of the extension rail as indicated at 11, although if the extension rails are made thin, as they may be for light work, this beveling will be unnecessary.

If we assume that the working face, instead of being as illustrated in Fig. 1, is closer to the ends of the track rails 4, the extension rails are then placed on top of the track rails with their forward ends very slightly projecting from the track rails. As, however, 15 the excavation or cut progresses, the car or other apparatus may be run backward on the track rails 4 and the extension rails pushed forward up to the working face, whereupon the car or apparatus may be run forward close to the working face, 20 and this operation is repeated as often as may be necessary. From time to time, as required, additional ties may be placed under the extension rails in order to keep 25 them to gage and to properly support them. In cases where the apparatus is light, such as an empty car, the extension rails may easily be pushed forward without even removing the car therefrom.

30 Although I have illustrated my extension rails and other rails as mounted upon metallic ties, they may, of course, be mounted upon the usual wooden ties, secured by spikes, or may be mounted on any other form 35 of metal tie or with other fastenings than those illustrated. It should also be noted that my extension rail is of such depth that as the extension rail fits over the track rail it just about clears the spikes or fastening 40 buttons 6, there being a slight space, as illustrated in Fig. 3, between the lower surfaces of the flanges 10 and the upper parts of the buttons 6, so that the upper part of my extension rail fits closely on the top 45 of the head of the track rail, thereby making a very trifling distance between the threads only equal to the slight thickness of the upper part of the extension rail. By beveling the ends of the extension rails as 50 illustrated, the distance between the treads where the wheels pass from the track rail to the extension rail, or vice versa, is reduced to nothing; so that the movement of 55 cars or other apparatus over the junction is easily accomplished, this rise being no greater than other usual irregularities in such tracks.

After the extension rails have been projected forward until only small portions of 60 their rear ends rest upon the front or forward ends of the track rails, another section of track rails of standard length may be put in their place, and the extension rails used in connection with this new pair of 65 rails. Rails used in mines and elsewhere

are generally of standard lengths, some 30 feet, 20 feet and 15 feet in length, and my extension rails can accordingly be made in any of the standard lengths of track rails, so as to temporarily take the place of any 70 of these, thus avoiding the necessity of supplying special lengths of track rails or of cutting and thereby spoiling the standard lengths on hand.

Although I have shown and described my 75 improvements in considerable detail, I do not wish to be limited to the exact and specific details shown and described, but may use such substitutions, modifications or equivalents thereof as are embraced within 80 the scope of my invention, or as pointed out in the claims.

Having thus described my invention, what I claim and desire to secure by Letters Patent is:—

1. The combination with a track rail of an extension rail adapted to fit throughout its length over the tread portion thereof and to be moved parallel and longitudinally thereof as desired.

2. The combination with a track rail of an extension rail of inverted U or channel form, the tread portion of which is adapted to be close to the tread portion of the track rail, said extension rail being adapted to 95 be moved longitudinally, while maintaining the proximity of said treads.

3. The combination with a track rail of an extension rail of inverted U or channel section, with integral flanges projecting outwardly from the extremities of the web portions, thereby stiffening the same and forming means for securing the extension rail to ties or gage rods, the tread portion of 100 said extension rail being adapted to rest 105 upon the tread of the track rail.

4. An extension rail of inverted U or channel section adapted to fit over a track rail with their tread portions adjacent, the end of the tread portion of said extension 110 rail being beveled.

5. The combination with the track rails of a pair of extension rails of inverted U section, with flanges extending outwardly 115 from the lower portions thereof, and means secured to said flanges for supporting and maintaining said extension track rails to gage.

6. The combination with the track rails of a pair of extension rails of inverted U section, with integral flanges extending outwardly from the lower portions thereof, a tie adapted to support said rails, provided with fastenings adapted to secure said rails by means of their flanges aforesaid.

7. The combination with the track rails of a pair of extension rails of inverted U section, provided with outwardly projecting flanges at the lower portions thereof, a metallic tie adapted to support said rails,

provided with rotatable button fasteners adapted to coöperate with said outstanding flanges to maintain the rails to gage.

8. A pair of extension rails of inverted 5 U section, provided with outwardly projecting flanges at the lower portions thereof, the ends of the tread portions of said extension rails being beveled, a metallic tie adapted to support said rails and provided with

fasteners adapted to coöperate with said outstanding flanges to maintain the rails to gage.

In testimony whereof I hereunto affix my signature in the presence of two witnesses.

EDWIN E. SLICK.

Copies of this patent may be obtained for five cents each, by addressing the "Commissioner of Patents.
Washington, D. C."

It is hereby certified that in Letters Patent No. 1,177,657, granted April 4, 1916, upon the application of Edwin E. Slick, of Westmont Borough, Pennsylvania, for an improvement in "Extension-Rails," errors appear in the printed specification requiring correction as follows: Page 1, line 21, for the article "The" read *In the*; same page, line 28, for the word "kept" read *keep*; line 34, for the word "extension" read *extensions*; line 66, for the word "construction" read *constructions*; line 102, for the words "metallic tie" read *Metallic Tie*; page 1, line 109, page 2, lines 25, 104, 118, page 3, lines 3, 13, for the word "gage" read *gauge*; page 2, line 2, for the word "easily" read *easily*; same page, line 47, for the word "threads" read *treads*; and that the said Letters Patent should be read with these corrections therein that the same may conform to the record of the case in the Patent Office.

Signed and sealed this 25th day of April, A. D., 1916.
